Henry Amrhein

Attorneys.

UNITED STATES PATENT OFFICE.

HENRY AMRHEIN, OF OXNARD, CALIFORNIA.

MACHINERY ALARM.

Application filed June 22, 1925. Serial No. 38,866.

To all whom it may concern:

Be it known that I, HENRY AMRHEIN, a citizen of the United States, and a resident of Oxnard, in the county of Ventura and 5 State of California, have invented a new and useful Machinery Alarm, of which the following is a specification.

The present invention relates to improvements in alarms for use in connection with 10 machinery.

The general object of the invention is the provision of an alarm adapted for use in connection with the clearance space of a reciprocating motor, pump, compressor or the 15 like to indicate a reduction in the size of said space, as when the piston moves beyond its normal distance of travel.

The above and other objects are accomplished by instrumentalities pointed out in 20 the following specification.

The invention is clearly defined in the claims.

A satisfactory embodiment of the invention is illustrated in the accompanying drawings forming part of the specification and in which:—

Figure 1 is a vertical, longitudinal section of the complete invention in use.

Figure 2 is a detail bottom plan view of 30 the invention in use, showing a fragment of a cylinder head.

Figure 3 is a fragmentary detail vertical section of a modification of the invention.

The clearance space *a* between the piston 35 5 and the head 6 of the cylinder may be that found in an ordinary gas or steam motor, pump, compressor or the like. The opening 7 in head 6 receives the reduced inner end portion of a casing 8, and the parts

40 are rigidly connected as by screw threads. An internally disposed valve seat 9 provides a support for a valve disk 10, which adjustably supports a plunger 11 extending through an opening in the valve and

45 connected thereto as by screw threads 12. The inner end of plunger 11 extends into clearance *a*, and adjacent to a point defining the limit of normal movement of piston 5 in one direction.

50 As a result of this adjustment of the plunger it can only contact with the piston when the same moves beyond its normal limit, as when the bearings or mountings of

any of the parts connected thereto become worn or fractured. A lock-nut 13, screwed upon plunger 11, prevents creeping of the plunger in a direction toward piston 5. The interior of the inner end portion of the casing is made a snug fit for the plunger and has two oppositely disposed open ended ports 14—15 through which communication is affected between clearance *a* and a chamber 16 within the casing 8, which communicates with the atmosphere through constricted outlets 17. Passage through the ports 14—15 is controlled by valve 10 which, when lifted by piston 5, causes a hissing sound or audible signal to be made by permitting the escape of compressed fluid from cylinder 6 into the atmosphere through constricted 70 openings 17.

A straight row of ratchet teeth 18 on one side of plunger 11, co-operate with a pawl 19 to render the audible signal continuous by automatically locking the plunger against 75 inward movement. The pawl is non-cylindrical in cross section and is slideable in a correspondingly shaped laterally disposed guide opening in casing 8. This construction prevents accidental turning of the pawl from engagement with the ratchet. A compression spring 20 urges the pawl 19 into contact with the ratchet, and yields to allow the ratchet to override the pawl in the outward movement of the plunger. 80

A housing 21, secured as by bolts 22, to casing 8, surrounds the outer end portion of the pawl and confines the spring 20. A cap 23 is detachably connected to the outer end 90 of the housing to provide a guide for an operating handle 24.

The handle 24 is slideable in an opening in the cap and is fixedly secured to the pawl and is manually operable to disengage the pawl from the ratchet when it is desirable to release the plunger to return to its normal position within the clearance *a*. 95

A plate 25, slideable within casing 8 and held against tilting, as by a socket 26 upon the outer end of plunger 11, provides a bearing for one end of a compression spring 27, which operates to hold valve 10 seated against the pressure of fluid within clearance *a*, acting through the ports 14—15. A 100 slideable plate 28, disposed upon the outer end of spring 27, is moved by an adjusting 105

screw 29 extending through a screw threaded opening in bonnet 30 to tension or compress spring 27 to the required extent. The bonnet 30 is detachably connected to casing 8, as by screw threads 31, and a lock nut 32 upon screw 29 prevents accidental turning thereof.

In the modified form shown in Figure 3, a plate 33, corresponding to plate 25, may be employed, during its outward movement under the action of plunger 34, to operate a rock arm 35 having one end extending into casing 36 through a lateral opening 37. A bracket 38, bolted as at 39, to the casing 36, is adapted as at 40, to provide a fulcrum for rock arm 36, which carries at its outer end a contact block 41 that is adapted to abut a contact block 42 on bracket 38 when arm 35 is moved by plate 33. The blocks 41-42 operate to close an electric circuit in which is connected an ordinary electric bell, (not shown), which operates by sounding, to give the required signal.

Although I have shown and described one embodiment of my invention, it is to be understood that the same is susceptible to various changes, and I reserve the right to employ such as may come within the scope of the appended claims.

I claim:—

1. An alarm for indicating reduction in the clearance of a cylinder having a reciprocating piston and comprising sound producing means, a plunger extending into the clearance of the cylinder and operable by the piston for setting the sound producing means in operation.

2. An alarm for indicating reduction in the clearance of a cylinder having a reciprocating piston and comprising sound producing means, a plunger extending into the clearance of the cylinder and operable by the piston for setting the sound producing means in operation and means for locking the plunger against return movement into the clearance, said means being manually operable to release the plunger.

3. An alarm for indicating reduction of the clearance of a cylinder having a reciprocating piston and comprising sound producing means including a casing connected to the cylinder, a plunger supported by the casing and extending into the clearance of the cylinder and operable by the piston for setting the sound producing means in operation.

HENRY AMRHEIN.
